UNITED STATES PATENT OFFICE

JAMES HOZACK, OF BELLEVILLE, NEW JERSEY, ASSIGNOR TO ESSEX ENGINE & MACHINE CORPORATION, A CORPORATION OF NEW JERSEY

BACK-FILLING MACHINE

Application filed June 25, 1928. Serial No. 288,001.

This invention relates particularly to a back-filling machine, that is a machine for pushing dirt back into a ditch or trench for the purpose of filling the same, although the invention is applicable to other different purposes, for example to road scrapers or graders or to other machines used for pushing operations.

One object of the invention is to provide a novel and improved construction in a machine of the character described comprising a suitable power driven unit, such as a tractor, having mounted thereon mechanism for pushing dirt or the like under the power of the tractor or the like, the invention being particularly directed toward the mounting and manipulation of the pushing mechanism on the power unit.

A further object is to provide a novel and improved construction of pushing mechanism and mounting thereof on the power driven unit whereby efficient leverage for operating of the pushing element is obtained so that the pushing element may be quickly raised and lowered with a small amount of energy.

Other objects are to provide a machine of this character comprising a sub-frame which is directly connected to the frame of the power unit or tractor and upon which is pivotally mounted intermediate its ends upon a horizontal axis and intermediate the ends of the power driven unit, a pusher frame having at one end in front of the power driven unit a pusher element, said pusher frame being swingable about its axis to raise and lower the pusher element by a power mechanism disposed at the rear of the power unit or tractor and connected between the rear end of the pusher frame and the rear end of the sub-frame; to provide such a machine where in the sub-frame and the pusher frame are substantially rectangular with the sub-frame arranged within the pusher frame and surrounding the power unit, said frames being in approximately the same horizontal plane; to provide means for connecting between the rear end of the sub-frame and the rear end of the pusher frame, a piston and cylinder device operated by a fluid pressure for swing-
ing the pusher frame, and to obtain other

advantages and results as will be brought out by the following description.

Referring to the accompanying drawings, in which corresponding and like parts are designated throughout the several views by the same reference characters—

Figure 1 is a side elevation of a back-filling machine embodying my invention, the power unit or tractor being shown schematically for clearness in illustration.

Figure 2 is a top plan view of the machine.

Figure 3 is a perspective view of the rear end of the machine with the fluid pressure pump and piping omitted, and

Figure 4 is a schematic illustration of the fluid pressure pump, piping and the piston and cylinder device.

Specifically describing the illustrated embodiment of the invention, the reference character A designates the chassis or body of a power unit which in the present instance is shown as a known type of tractor having the usual self-laying tracks B. The frame or chassis A of the tractor has a shaft C projecting from opposite sides thereof and supporting the endless track guides D, and it is upon the ends of this shaft that the sub-frame E of my pushing mechanism is mounted.

This sub-frame is substantially rectangular in plan view and comprises sides 1 and ends 2 which are shown as formed of I-beams connected together at their ends so that the frame surrounds the tractor or power unit as clearly shown in Figure 2 of the drawings. Intermediate their ends the side pieces 1 have secured thereto bearing members 3 which are fitted upon the ends of the shaft C by nuts 4. The forward end of the sub-frame E, that is the end of the frame at the front of the tractor, is connected to the body of the chassis of the tractor in any suitable manner. As shown, cap screws 200 passing through openings 201 in the end piece 2 of the frame E, are threaded into the chassis.

At the rear end of the sub-frame E, means is provided which both connects said frame to the chassis of the tractor and also serves for connecting the power mechanism for operating the pusher frame to the sub-frame and

the pusher frame F. This means is shown as consisting of a special plate 5 secured to the rear end of the chassis and having an opening 6 through which the power shaft of the tractor extends. The top of this plate 5 is formed with a lug 7 to which is connected by a bolt 8 a pair of angle irons 9 which extend upwardly and rearwardly and have their outer ends bent so as to be disposed in a substantially horizontal plane, as indicated at 10. To the outer ends of angle irons 10 is connected the base portion of a substantially inverted U-shaped strut 11 having its ends connected to the rear end of the sub-frame by bolts or the like 12. The strut and angle irons 9 thus form a tripod with one foot on the tractor and the other two feet upon the sub-frame.

The pusher frame F is also substantially rectangular and comprises side pieces 13 and end pieces 14 connected at their ends so as to surround the sub-frame E. The side pieces 13 are pivotally connected on a horizontal axis intermediate their ends to the side pieces 25 of the sub-frame E intermediate the ends of the latter as indicated at 15. This pivotal connection is shown as comprising a pair of plates 16 one secured to the web of each side pieces 1 and 13 and having a pivot pin 17 passing therethrough. The pusher frame F is therefore swingable about the horizontal axis. The ends of the side pieces 13 extend beyond the front end piece, 14 and a pusher element 18 is connected to the pusher frame 30 at this end in any suitable manner. As shown the pusher element comprises a plate 19 having at its rear side four pairs of vertically disposed angle irons 20 between the flanges of each pair of which is connected adjacent the upper ends thereof one end of a strut 21, the other end of which is connected as at 22 to the pusher frame. The lower ends of the flanges 20 are similarly connected by struts 23 to the pusher frame except that the 40 end pairs of angle irons 20 are connected to the outer ends of large struts 24 the other ends of which are riveted at 25 to the webs of the extremities of the side pieces 13. With this construction it will be observed that by 45 swinging the rear end of the sub-frame F the pusher 18 may be raised and lowered. It will also be observed that the particular arrangement and pivotal mounting of the pusher frame F provides efficient leverage 50 for so swinging the pusher frame, and the strains incident to both the weight of the pushing apparatus and the resistance produced by pushing operations are applied to the power unit or tractor at approximately 55 the center thereof so that great power is efficiently utilized.

Any suitable means may be used for swinging the pusher frame to raise and lower the pusher, but preferably a fluid pressure mechanism, particularly a hydraulic apparatus,

is employed. Accordingly I have shown the cylinder 26 pivotally connected at one end 27 to the rear end of the pusher frame F and having a piston 28 therein which is provided with a piston rod 29 extending from the other end of the cylinder and pivotally connected at 30 to the outer ends 10 of the angle irons 9. This cylinder has at its opposite ends hose connections 31 for permitting oil under pressure to be supplied and exhausted from the respective ends of the cylinder. These hose connections are in turn connected by pipes 32 to two ports of a four-way valve 33, the other two ports of which are connected by pipes 34 and 35 to a pump 36. This pump may be of any suitable construction, preferably a rotary pump, and is shown as mounted by brackets 37 upon the plate 5. The shaft of the pump is connected to the shaft 38 of the tractor by any suitable coupling (not shown). With this construction, and with particular reference to Figure 4 of the drawings, it will be observed that the oil in the system may be alternately supplied to and exhausted from the ends of the cylinder 26 by manipulation of the valve 33, and thereby may the pusher frame F be swung to raise and lower the pusher 18. Ordinarily the pressure in the pipes 32, 34, and 35 is sufficient to operate the piston and cylinder 40 device 26, 28 and to provide for excess pressure under any conditions, for example, when the pushing apparatus is not being operated I may connect a tank 39 by pipes 40 to opposite sides of the pump 36 and insert a 45 pressure regulating valve 41 in the piping to permit by-passing of the oil through the tank when a pre-determined pressure is reached. This construction is in general old and well-known and no claim to novelty 50 is made thereon.

The operation of the machine will be understood from the foregoing but may be summarized as follows: The pusher 18 is normally raised from the ground during movement of the tractor A which is operated in the usual way, the pusher being held off the ground by operation of the piston and cylinder mechanism 26, 28 by proper manipulation of the valve 33 which is preferably 55 arranged adjacent the seat of the operator of the tractor and controlled by a suitable lever 42. When it is desired to lower the pusher to the ground the valve handle 42 is moved to the dotted line position of Figure 60 4, while when it is desired to raise the pusher, the valve handle is moved to the solid line position of Figure 4. Obviously, at any time the valve handle 42 can be swung into neutral or vertical position on Figure 4 to 65 trap the oil in both ends of the cylinder and lock the piston against movement in either direction.

It will be understood that the specific details of construction herein described are 70

primarily for the purpose of illustrating the principles of the invention and that many modifications and changes may be made without departing from the spirit or scope 5 of the invention.

The term "tractor" as used in the following claims is intended to include all power driven vehicles or traveling carriages.

Having thus described my invention, what 10 I claim is:

1. A machine of the character described comprising a tractor, sub-frame members mounted on said tractor at opposite sides of the same in enclosing relation with respect 15 to the running gear thereof and fixed with respect to said tractor, a pusher frame pivotally mounted on said sub-frame members outside the same to swing about a horizontal axis, a pusher on said pusher frame, and means 20 for swinging said pusher frame about said axis.

2. A machine of the character described comprising a tractor, a sub-frame mounted on said tractor in enclosing relation with respect to the running gear thereof and fixed with respect to said tractor, a pusher frame pivotally mounted on said sub-frame outside the same to swing about a horizontal axis, a pusher on said pusher frame, and 25 means for swinging said pusher frame about said axis.

3. A machine of the character described comprising a tractor, a substantially rectangular sub-frame mounted thereon and surrounding the same, a pusher frame pivotally mounted on the sides of said sub-frame outside the same to swing about a horizontal axis and having a pusher at one end in front of said tractor, and means for swinging said 30 pusher frame about said axis.

4. A machine of the character described comprising a tractor, a substantially rectangular sub-frame mounted thereon and surrounding the same, a pusher frame pivotally mounted intermediate its ends on the sides of said sub-frame to swing about a horizontal axis and having a pusher at the front end ahead of said tractor, and means connected between the rear ends of said 45 frames for swinging said pusher frame about said axis.

5. A machine of the character described comprising a tractor, a substantially rectangular sub-frame mounted thereon and surrounding the same, a pusher frame pivotally mounted intermediate its ends on the sides of said sub-frame to swing about a horizontal axis and having a pusher at the front end ahead of said tractor, a cylinder and piston each having one end pivotally connected to one of said frames so as to swing the pusher frame upon relative movement of the cylinder and piston, and means for supplying and exhausting fluid under pressure to and from opposite ends of said cylinder to cause 50

relative movement of the cylinder and the piston.

6. A machine of the character described comprising a tractor, sub-frame members mounted on said tractor at opposite sides of the same in enclosing relation with respect to the running gear thereof and fixed with respect to said tractor, a pusher frame pivotally mounted on said sub-frame members outside the same to swing about a horizontal axis, a cylinder and piston having their opposite ends pivotally connected to said frames so as to swing the pusher frame upon relative movement of the cylinder and piston, and means for supplying and exhausting fluid under pressure to and from opposite ends of said cylinder to cause relative movement of the cylinder and piston. 70

7. A machine of the character described comprising a tractor, a sub-frame mounted on said tractor in enclosing relation with respect to the running gear thereof and fixed with respect to said tractor, a pusher frame pivotally mounted on said sub-frame outside the same to swing about a horizontal axis, a cylinder and piston having their opposite ends pivotally connected to said frames so as to swing the pusher frame upon relative movement of the cylinder and piston, and means for supplying and exhausting fluid under pressure to and from opposite ends of said cylinder to cause relative movement of the cylinder and piston. 75

8. A machine of the character described comprising a tractor including a frame having a transverse shaft therein the ends of which extend at opposite sides of said frame, a sub-frame connected to said ends of said shaft, means connecting said sub-frame to the front of said tractor frame, a pusher frame pivotally mounted on the outer sides of said sub-frame to swing about a horizontal axis, a pusher at one end of said pusher frame ahead of said tractor, and means connected to the other end of said pusher frame for swinging the same about said axis. 100

9. A pushing device for a tractor, comprising a substantially rectangular sub-frame for mounting on the tractor and surrounding the same, a pusher frame pivotally mounted on the sides of said sub-frame outside the same to swing about a horizontal axis and having a pusher at one end in front of said tractor, and means for swinging said pusher frame about said axis. 115

10. A pushing device for a tractor having a transverse shaft the ends of which extend at opposite sides of said tractor comprising a sub-frame for mounting on said ends of said shaft, means for connecting said sub-frame to the front of said tractor frame, a pusher frame pivotally mounted on the outer sides of said sub-frame to swing about a horizontal axis, a pusher at one end of said pusher frame ahead of said tractor, and 120

125

130

- means connected to the other end of said pusher frame for swinging the same about said axis.
11. A machine of the character described comprising a tractor, a sub-frame mounted thereon and surrounding the same in fixed relation thereto, a pusher frame outside said sub-frame pivotally mounted on the sides thereof to swing about a horizontal axis and having a pusher at its end in front of said tractor, and means for swinging said pusher frame about said axis.
12. A machine of the character described comprising a tractor, a sub-frame surrounding the same and connected to the front and sides thereof, a pusher frame outside the sub-frame pivotally mounted intermediate its ends on the sides of said sub-frame to swing about a horizontal axis and having a pusher at the front end ahead of said tractor, and means connected between the rear ends of said frames for swinging said pusher frame about said axis.
13. A machine of the character described comprising a tractor, a sub-frame mounted on said tractor in enclosing relation with respect to the running gear thereof and fixedly connected to the front and rear of said tractor, a pusher frame pivotally mounted on said sub-frame outside the same to swing about a horizontal axis, a pusher on said pusher frame, and means for swinging said pusher frame about said axis.
14. A machine of the character described comprising a tractor, a sub-frame surrounding the same and fixed thereto, a pusher frame outside said sub-frame and connected thereto for bodily swinging movement thereon, a pusher on said pusher frame, and means for swinging said pusher frame.
15. A machine of the character described comprising a tractor provided with lateral projections, a sub-frame surrounding said tractor and mounted on said projections in fixed relation to the tractor, a pusher frame pivotally mounted on said sub-frame, a pusher on said pusher frame, and means for swinging said pusher frame.
16. The combination with a tractor provided with shaft ends projecting from the sides thereof beyond the traction elements of said tractor, a sub-frame mounted on said shaft ends outside of and enclosing said traction elements and connected to the front of the tractor, a pusher frame mounted on said sub-frame, a pusher on said pusher frame, and means for swinging said pusher frame with respect to said sub-frame.
17. The combination with a tractor provided with shaft ends projecting from the sides thereof beyond the traction elements of said tractor, a sub-frame mounted on said shaft ends outside of and enclosing said traction elements and connected to the front and the rear of the tractor, a pusher frame
- mounted on said sub-frame, a pusher on said pusher frame, and means for swinging said pusher frame with respect to said sub-frame.
18. Combined with a tractor of the traction belt type, an enclosing sub-frame mounted on said tractor in fixed relation thereto, a pusher frame pivoted on said sub-frame, a pusher attached to the front end of said pusher frame, and means at the rear for depressing the pusher frame for elevating the

24. A machine of the character described comprising a tractor, a substantially rectangular sub-frame mounted thereon and surrounding the same in fixed relation thereto, a substantially rectangular pusher frame pivotally mounted on the sides of said sub-frame to swing about a horizontal axis, a pusher at one end of said pusher frame, and means at the other end of said pusher frame for swinging it about its said axis. 70
25. A machine of the character described comprising a tractor, a substantially rectangular sub-frame surrounding said tractor and fixedly connected to the front and sides thereof, a substantially rectangular pusher frame outside said sub-frame and pivotally mounted on the sides thereof to swing about a horizontal axis, a pusher at the front end of said pusher frame, and means connected between the rear ends of said frames for swinging said pusher frame about its said axis. 75
26. A machine of the character described comprising a tractor, sub-frame members mounted on said tractor at opposite sides of the frame in enclosing relation with respect to the running gear thereof and fixed with respect to said tractor, a substantially rectangular pusher frame outside said tractor and sub-frame and pivotally mounted on said sub-frame members to swing about a horizontal axis, and means for swinging said pusher frame about said axis. 80
27. The combination of a tractor provided with lateral projections, a substantially rectangular sub-frame mounted on said projections in fixed relation to the tractor, a pusher frame mounted on the sides of said sub-frame outside the same, and means for swinging said pusher frame with respect to said sub-frame. 85
28. The combination with a tractor provided with bearings projecting laterally from the sides thereof beyond the traction elements on said tractor, a substantially rectangular sub-frame having its side members mounted on said bearings, said members being bent upward forward of said bearings and secured to the tractor across the front thereof, a pusher frame pivotally mounted on said sub-frame members to swing about a horizontal axis, and means for swinging said pusher frame about said axis. 90
29. The combination of a tractor provided with lateral projections, a substantially rectangular sub-frame mounted on said projections and fixedly connected to the front and rear of the tractor, a pusher frame mounted on said sub-frame, and means for swinging said pusher frame with respect to said sub-frame. 95
30. The combination of a tractor provided with lateral projections, a sub-frame mounted on said projections and fixedly connected to the tractor, a substantially rectangular sub-frame mounted on said projections in fixed relation thereto, a substantially rectangular pusher frame pivotally mounted on the sides of said sub-frame to swing about a horizontal axis, a cylinder and piston having their opposite ends pivotally connected to the rear ends of said frames, and means for supplying and exhausting fluid under pressure to and from opposite ends of said cylinder to cause relative movement of the cylinder and piston. 100
31. A pushing device for a tractor comprising sub-frame members for mounting on said tractor at opposite sides of the same in enclosing relation with respect to the running gear thereof and fixed with respect to the tractor, a pusher frame pivotally mounted on said sub-frame members outside the same to swing about a horizontal axis, and means for swinging said pusher frame about said axis. 105
32. A pushing device for a tractor comprising a sub-frame for mounting on the tractor and surrounding the same in fixed relation thereto, a pusher frame pivotally mounted on the sides of said sub-frame outside the same to swing about a horizontal axis, and means for swinging said pusher frame about said axis. 110
33. A pushing device for a tractor comprising a substantially rectangular sub-frame for mounting on the tractor and surrounding the same in fixed relation thereto, a substantially rectangular pusher frame pivotally mounted on the sides of said sub-frame to swing about a horizontal axis, and means for swinging said pusher frame about said axis. 115
34. A pushing device for a tractor comprising a substantially rectangular sub-frame for mounting on the tractor and surrounding the same in fixed relation thereto, a substantially rectangular pusher frame pivotally mounted on the sides of said sub-frame to swing about a horizontal axis, and means between the rear ends of said frames for swinging said pusher frame about its said axis. 120
35. A pushing device for a tractor comprising a substantially rectangular sub-frame for mounting on the tractor and surrounding the same in fixed relation thereto, a substantially rectangular pusher frame pivotally mounted on the sides of said sub-frame to swing about a horizontal axis, a cylinder and piston having their opposite ends pivotally connected to the rear ends of said frames, and means for supplying and exhausting fluid under pressure to and from opposite ends of said cylinder to cause relative movement of the cylinder and piston. 125
36. A machine of the character described comprising a tractor, a sub-frame fixedly mounted upon said tractor in enclosing relation thereto, a pivoted pusher frame also in enclosing relation to the tractor, and means for swinging said pusher frame with respect to said sub-frame. 130
37. A machine of the character described comprising a tractor, a sub-frame fixedly mounted upon said tractor in enclosing relation thereto, a pivoted pusher frame also in enclosing relation to the tractor, and means connecting said frames for swinging the

pusher frame with respect to the sub-frame.

38. The combination with a tractor provided with lateral projections, of a sub-frame mounted on said projections in fixed relation to the tractor, a pivoted pusher frame in enclosing relation to the tractor, and means for swinging said pusher frame with respect to said sub-frame.

39. The combination with a tractor provided with lateral projections, of a sub-frame mounted on said projections and fixedly connected to the rear of the tractor, a pivoted pusher frame in enclosing relation to the tractor, and means for swinging said pusher frame with respect to said sub-frame.

40. The combination with a tractor, of an enclosing sub-frame having side members and a back member all fixedly connected to the tractor, a pusher frame pivoted in enclosing relation to the tractor, and means for swinging said pusher frame with respect to said sub-frame.

41. The combination with a tractor, of a sub-frame extending across the back of the tractor outside of the same and fixedly secured thereto, a pusher frame pivoted at the sides of the tractor and extending across the front thereof in enclosing relation to the sub-frame, and means for swinging said pusher frame with respect to said sub-frame.

42. A machine of the character described comprising a tractor, a sub-frame fixedly mounted thereon, a pusher frame pivotally mounted outside said sub-frame to swing upon a horizontal axis without interfering with said sub-frame, a pusher on said pusher frame, and means for swinging said pusher frame about said axis.

43. A machine of the character described comprising a tractor, a sub-frame fixedly mounted thereon, a pusher frame pivotally mounted outside said sub-frame to swing upon a horizontal axis without interfering with said sub-frame, a pusher on said pusher frame, and means connected to said sub-frame and pusher frame for swinging the latter.

44. A machine of the character described comprising a tractor, a sub-frame fixedly mounted thereon in enclosing relation thereto, and extending across the rear of the tractor, a pusher frame pivotally mounted outside said sub-frame to swing upon a horizontal axis without interfering with said sub-frame and having a pusher at the front of the tractor, and means connected to said sub-frame and pusher frame for swinging the latter.

45. A machine of the character described comprising a tractor provided with lateral projections, a sub-frame mounted on said projections in fixed relation to the tractor, a pusher frame pivotally mounted outside said sub-frame to swing upon a horizontal axis without interfering with said sub-frame, a pusher on said pusher frame, and means for

swinging said pusher frame about said axis.

46. A machine of the character described comprising a tractor provided with lateral projections, a sub-frame mounted on said projections in fixed relation to the tractor, a pusher frame pivotally mounted outside said sub-frame to swing upon a horizontal axis without interfering with said sub-frame, a pusher on said pusher frame, and means connected to said sub-frame and pusher frame for swinging the latter.

47. A machine of the character described comprising a tractor provided with lateral projections, a sub-frame mounted on said projections and extending across the rear of the tractor in fixed relation thereto, a pusher frame pivotally mounted at the sides of the tractor to swing upon a horizontal axis and having a pusher at the front of the tractor, and means connected to said sub-frame and pusher frame for swinging the latter.

48. A machine of the character described comprising a tractor, a sub-frame fixedly mounted thereon and extending across the rear of the tractor, a pusher frame pivoted to swing upon a horizontal axis and having a pusher at the front of the tractor, and means connected to said sub-frame and pusher frame for swinging the latter.

49. A machine of the character described comprising a tractor provided with lateral projections, a sub-frame mounted on said projections in fixed relation to the tractor and extending across the rear thereof, a pusher frame pivoted to swing upon a horizontal axis and having a pusher at the front of the tractor, and means connected to said sub-frame and pusher frame for swinging the latter.

50. A machine of the character described comprising a tractor, a sub-frame mounted on said tractor in fixed relation thereto, a pusher frame pivoted to swing upon a horizontal axis intermediate the ends of the tractor without striking said sub-frame, a pusher on said pusher frame at the front of the tractor, and means connected to said sub-frame and pusher frame for swinging the latter.
